CARRIAGE FOR ACCOUNTING MACHINES

Raymond A. Christian, Dayton, Ohio, assignor to
The National Cash Register Company, Dayton,
Ohio, a corporation of Maryland

Original application January 2, 1932, Serial No.
584,438. Divided and this application October
28, 1933, Serial No. 695,661

4 Claims. (Cl. 197—127)

This invention relates to accounting or book-keeping machines and the like, but more particularly to machines of this type having a traveling carriage such as are set out and described in Letters Patent of the United States Nos. 1,197,276 and 1,197,278 issued September 5, 1916 to Halcolm Ellis, and Patent No. 1,203,863 issued November 7, 1916 to Halcolm Ellis; and is a division of the application for United States Letters Patent of Raymond A. Christian Serial Number 584,438 filed January 2, 1932.

One object of this invention is to provide a traveling carriage with a novel slip receptacle or chute which may be used alone on the carriage or in conjunction with a card chute or other types of receptacles such as illustrated in the parent application above mentioned.

Another object of this invention is to provide normal means on the slip chute for concealing the printing in a particular column of the slip.

Another object in addition to the concealing means is to provide novel means whereby only the printing line of the slip in the chute is exposed to view in other particular columns of said slip.

Another and more specific object of this invention is to provide the slip chute with a hinged member which may be used to conceal the printing in any desired one of the vertical columns.

With these and incidental objects in view the invention includes certain novel features of construction and combinations of parts, the essential elements of which are set forth in appended claims and a preferred form of embodiment which is hereinafter described with reference to the drawings which accompany and form part of this specification.

Of said drawings:

Fig. 1 is a perspective view of the slip receptacle or chute.

Fig. 2 is an end view of the slip chute as observed from the right.

Fig. 3 is a perspective view, in reduced scale, showing a portion of a carriage and a platen, and illustrates the slip chute mounted in position on the carriage.

General description

The present invention is incorporated in a machine of the well known Ellis type having a traveling carriage. This invention in the preferred form includes a slip receptacle mounted upon the traveling carriage in such a way that material placed therein is interposed between the printing type and the platen roll.

The slip chute has a plurality of compression rolls which hold the slips inserted therein securely against the platen roll so that such slips will be automatically fed by said platen roll. Convenient means for releasing the compression rolls is supplied for use when removing or inserting slips.

As set forth in the objects the novel slip chute is provided with means for concealing the printing in one of the columns when desired, also with means for concealing all of the printing in the remaining columns except that on the printing line when desired.

DETAILED DESCRIPTION

Traveling carriage and platen

Only so much of the platen and traveling carriage have been shown in this case as is necessary to illustrate the relative location of applicant's novel slip receptacle or chute to the platen and carriage.

A usual platen roll 44 is journaled at one end in arm 39 on a traveling carriage frame 45 (Fig. 3). The carriage frame 45 is slidably mounted on a machine case 46 which incloses the machine mechanism and is in turn supported by a machine base (not shown).

Slip receptacle or chute

The traveling carriage frame 45 of the present machine is equipped with a slip receptacle or chute 118 (Figs. 1, 2, and 3) which as previously stated may be used alone or in conjunction with a card chute such as shown in the parent application above referred to.

Fig. 3 well shows the location of the slip chute upon the traveling carriage and its position in relation to the platen while Figs. 1 and 2 illustrate in detail the construction of the slip chute 118. Referring to Fig. 1, the slip chute 118 includes a pair of end plates 113 and 114 supported by rods 47 and 48 carried by a pair of carriage end plates 50 (only one of which is shown, Fig. 3) which in turn are carried by the shaft of the platen 44 and travel as a unit with the traveling carriage. Rods 116 and 117 (Figs. 1 and 2) and shafts 120 and 121 extend the width of the slip chute 118 and connect the plates 113 and 114. A guide plate 122 is secured to the rod 116 and is also supported by the rods 117 and 48. The guide plate 122 is formed around the platen roll 44; ample clearance being allowed between the guide plate and platen roll for the insertion of slips therebetween. The guide plate 122 is sup-

55

ported at its front end by projection 123 thereon bent around the rod 47. The guide plate 122 has a plurality of openings 124 through which the printing type 38 makes contact with the slip.

5 Hinged to the rod 47 and straddling one of the projections 123 is a cover 125 (Fig. 1) which may be used to hide from view matter printed in one of the columns on the slip. Also hinged to the rod 47 between the cover 125 and another of 10 the projections 123 is a cover 126 having a slot 127. When the cover 126 is in place over one of the openings 124 only the matter on the printing line is visible through the slot 127.

15 The shaft 120 (Fig. 1) has secured thereon a pair of adjustable tension collars 128 each having a hole into which is inserted one end of a pair of springs 129. The other end of each spring 129 is inserted in a hole in each of a pair of tension arms 130. The arms 130 each have secured thereto a hub 131 by means of which said arms are pivoted on the shaft 120. The hubs 131 are each partly cut away on their face to form a step which is adapted to cooperate with like steps cut in adjustable release collars 132 20 secured to the shaft 120 for a purpose to be later described. Pivoted between the arms 130 is a compression roll shaft 133 having pivoted thereon a plurality of compression rolls 134 held in position by clips 139. A release arm 135 secured 25 to the right end of the shaft 120 carries a stud 136 which is adapted to cooperate with a cam slot 137 in a release lever 138 pivoted on the rod 48.

30 The shaft 121 is similar to the shaft 120 and carries two tension arms 140 each having a stepped hub 141, two tension collars 142, two tension springs 143 and two stepped release collars 144. The arms 140, hubs 141, collars 142, springs 143 and collars 144 are identical with the arms 40 130, hubs 131, collars 128, springs 129 and collars 132 respectively, and therefore, only one of each of the former elements is shown in Fig. 1. The arms 140 support a shaft 145 carrying tension rolls 146 held in place by clips 139. Also 45 secured to the right end of the shaft 121 is a release arm 150 carrying a stud 151 cooperating with cam slot 152 in the release lever 138.

50 The steps on the hubs 131 and 141 and the steps on the collars 132 and 144 are cut off center to allow the arms 130 and 140 to be moved independently of the collars 132, to the end that when the release lever 138 is in the position shown in Figs. 1 and 2, the rolls 134 and 146 under tension of the springs 129 and 143 will be urged toward 55 the platen roll 44 thereby firmly holding the slip inserted between said rolls and platen so that feeding of said slip will be effected by rotating the platen roll 44 in the usual manner.

60 When removing a slip from the chute or when placing a new slip within the chute it becomes necessary to move the rolls 134 and 146 away from the platen 44. This is accomplished by moving the lever 138 clockwise which causes the cam slots 137 and 152 to coat with the studs 136 65 and 151 to rock the arm 135 and shaft 120 clockwise, and the arm 150 and shaft 121 counter-clockwise. This causes the steps on the collars 132 and 144 to engage the steps on the hubs 131 and 141 to rock the rolls 134 and 146 away from the platen roll 44.

65 Let us assume that the present invention is being used on a machine by a telephone company in a large city having a great number of subscribers. The system used by this company requires that its subscribers pay a flat rate for a 70

certain number of calls, say seventy-five, and five cents per call for all over seventy-five calls. Each subscriber's phone has a register or step by step counter located at the central office or exchange which accumulates one each time the subscriber makes a call. These registers each have an identification number which is generally the same as that of the telephone they represent.

75 The monthly calculation of each subscriber's account takes place upon a "work sheet" or slip 10 187 (Fig. 3) which is arranged to take care of the monthly statement of one hundred subscribers who are listed numerically by telephone or register number in a column headed telephone or register number. At a fixed time each month a 15 reading is taken of the telephone registers by photographing them in blocks of one hundred. Prints of these photographs are turned over to the machine operators for the purpose of copying the register readings upon the work sheet which 20 is accomplished thus.

25 The operator releases the slip chute compression rolls 134 and 146 (Fig. 1) by moving the lever 138 clockwise. The "work sheet" or slip 187 representing, in the illustrative case, the register numbers 3800 to 3899 is then inserted in the slip chute, adjusted until the line bearing the first register number is in line with the printing type and is then clamped in position by releasing the lever 138. The operator then raises the cover 125 30 which previously obscured the column headed "present reading" and copies therein the register reading taken from the photographic print of the registers 3800 to 3899 inclusive. The machine is arranged to automatically feed the work sheet in 35 the usual manner from line to line near the end of each operation.

40 After having copied all the register readings the operator in a clearing operation of the machine prints the total thereof at the foot of the "present reading" column. The cover 125 is then closed, the cover 126 raised, the "work sheet" returned to the starting position and the traveling carriage tabulated until the column headed "proof reading" is in horizontal alignment with 45 the printing type. In this column the operator again copies the register readings from the photographic print and takes a total thereof, the same as before. This total is compared with the previous total for the purpose of detecting errors 50 in the copying of the register readings.

55 When finished with one account the work sheet is automatically turned upward to the next line bearing the register number 3801.

When the minimum number of calls (75) allowed by this contract has not been exceeded this fact will be manifest to the operator when the gross number of calls is printed in the "gross usage" column on the "work sheet".

60 While the form of mechanism herein shown and described is admirably adapted to fulfill the objects primarily stated, it is to be understood that it is not intended to confine the invention to the one form of embodiment herein disclosed for it is susceptible of embodiment in various 65 forms all coming within the scope of the claims which follow.

66 What is claimed is:

70 1. In a machine of the class described having printing means and a traveling carriage carrying a platen roll; the combination of a slip chute adapted to laterally locate slips having a plurality of vertical columns in proper relation to the printing means; means on the slip chute for concealing the printing in a particular column of the

slip; and means for causing only the printing line to be exposed to view in other particular columns of the slip.

2. In a machine of the class described having printing means and a traveling carriage with a platen roll; the combination of a slip chute carried by the traveling carriage, said slip chute adapted to locate slips having a plurality of vertical columns in proper lateral relation to the printing means; a hinged member on the slip chute adapted to conceal the printing in one of the vertical columns when desired; and another hinged member on the slip chute having therein an opening which exposes to view the printing line only of certain other columns.
3. In a machine of the class described having printing means and a traveling carriage with a platen roll; the combination of a slip chute carried by the traveling carriage, said slip chute adapted to locate slips having a plurality of vertical columns in proper lateral relation to the printing means; a hinged member on the slip chute adapted to conceal the printing in one of the vertical columns when desired; and another hinged member on the slip chute having therein an opening which exposes to view the printing line only of certain other columns.
4. In a machine of the class described having printing means and a traveling carriage with a platen roll; the combination of a slip chute carried by the traveling carriage, said slip chute adapted to locate slips having a plurality of vertical columns in proper relation to the printing means; hinged means on the slip chute adapted to conceal the printing on the printing line and on all of the lines adjacent thereto in one of the vertical columns; and additional hinged means located adjacent said first hinged means and having therein an opening which exposes to view the printing line only of certain other columns.
